UNITED STATES PATENT OFFICE.

EDWARD W. ROBINSON, OF SAVANNAH, GEORGIA, ASSIGNOR TO INTERNATIONAL BARREL COMPANY, OF SAVANNAH, GEORGIA, A CORPORATION OF GEORGIA.

DIE-PRESS.

1,175,663.

Specification of Letters Patent. Patented Mar. 14, 1916.

Application filed January 7, 1915. Serial No. 945.

To all whom it may concern:

Be it known that I, EDWARD W. ROBINSON, a citizen of the United States, residing in Savannah, Georgia, have invented certain Improvements in Die-Presses, of which the following is a specification.

My invention consists of a press for so acting, by means of dies, upon a sheet metal ring having an angular cross section as to produce a hoop consisting of a ring having substantially parallel flanges projecting at an angle therefrom at each edge, one of said flanges also having, if desired, an inwardly projecting flange at its free edge.

In the accompanying drawings—Figure 1 is a front elevation of a die press made in accordance with my invention; Fig. 2 is a view, partly in side elevation and partly in section; Figs. 3 and 4 are diagrammatic views illustrating the successive actions of the dies; Fig. 5 is a perspective view of the blank from which the hoop is to be produced; Fig. 6 is a perspective view of the finished hoop, and Fig. 7 is a side elevation of part of the press, illustrating a special feature of my invention.

As shown in Fig. 5 the blank from which the hoop is to be produced consists of a split ring presenting in cross section flanges 1 and 2 and a connecting web 3, the latter being at right angles or thereabout to the flanges 1 and 2, which are in parallel or substantially parallel planes. The purpose of the die press constituting the subject of my present invention is to convert this ring-shaped blank into a hoop of the character shown in Fig. 6, and consisting of a ring member 4 with outer and inner flanges 5 and 6 projecting therefrom at a right angle or thereabout, the inner flange 5 having at its free edge, an inwardly projecting flange 7 parallel or substantially parallel with the ring member 4 of the hoop, although this flange may be omitted if desired.

Although I have shown both the blank and the hoop as in the form of split rings the ends may be welded together if desired before subjecting the blank to the action of the press, and the term "ring" as used herein therefore means either a split ring or a continuous ring.

In Figs. 1 and 2, 10 represents the bed of the press having seated therein a plate 11 with projecting annular die 12, said bed 55 also supporting a cross head 13 in which

is vertically guided a plunger 14 splined or otherwise engaged with said cross head so that while it is susceptible of free vertical movement through the same it cannot turn therein. The plunger 14 is tubular and guided within it is a smaller plunger 15, and each of these plungers carries a die at its lower end, that of the outer plunger being represented at 16 and that of the inner plunger at 17.

The die 16 is in the form of an inverted cup whose outer annular flange operates in connection with the outer face of the annular die 12 and the die 17 is a circular plate operating within the same in conjunction with the upper face of said die and also in conjunction with a ring die 18 disposed adjacent to the inner face of the die 12 and movable vertically in an annular recess in the plate 11, being normally projected by means of one or more coiled springs 19 interposed between the base of said recess and the under face of the ring die 18, as shown in Fig. 2.

The plunger 14 has at the top a head 20 carrying anti-friction rollers 21 which are acted upon by cams 22 on a transverse shaft 23, and the inner plunger 15 has, at the top, an anti-friction roller 24 which is acted upon by a cam 25 on said shaft. The shaft 23 is carried by boxes 26 which are vertically guided in standards 27 at opposite sides of the cross head 13, said boxes resting upon tapered gibs 28 which can be adjusted by means of set screws 29 so as to raise or lower, to a limited extent, the boxes 26 and the shaft carried thereby. The cams 22 also act upon anti-friction rollers 30 carried by an upper shaft 31 which is mounted in boxes 32 movable vertically in guides 33 mounted on the standards 27, said shaft 31 being connected by yokes 34 to the head 20 of the plunger 14, as shown in Fig. 1.

The shaft 23 may be rotated in any suitable manner, being in the present instance provided with a clutch 35 whereby it can be connected to or disconnected from a spur wheel 36, loosely mounted on the shaft, and driven by means of a spur pinion 37 from a power shaft 38 adapted to a bearing carried by an arm 39 projecting from the bed 10 of the press. The clutch 35 is conveniently operated through the medium of a lever 40 and handle 41, or in any other suitable way.

The plunger 14 has a longitudinal slot 110

42 therein for the reception of a lug 43 projecting from the inner plunger 15, or a plurality of such slots and lugs may be employed if desired. Depression of the plunger 14 is effected by action of the cams 22 upon the anti-friction rollers 21 on the head of said plunger and depression of the inner plunger 15 is effected by the action of the cam 25 upon the anti-friction roller 24 carried by said plunger 15, lifting of the plungers being effected by the action of the cams 22 upon the anti-friction rollers 30 on the upper shaft 31, which, through the medium of the lugs 34, lifts the plunger 14, this lifting movement being imparted to the inner plunger 15 through the medium of the lug 43, but, owing to the slot 42, commencing at a later period than the lift of the plunger 14.

20 In the operation of the press the ring-shaped blank is laid upon the top of the annular die 12, when the dies 16 and 17 are raised above said die 12, the inner portion of the flange 1 resting upon the top of said die 12, the member 3 extending downwardly along the inner side of said die and the flange 2 resting upon the top of the ring die 18. The die 17 first descends and clamps the flange 1 upon the top of the die 12 and the flange 2 upon the ring die 18, as shown in Fig. 3, so that the blank is firmly confined to the die 12 with the flange 1 projecting outwardly from the top of said die.

35 On the descent of the die 16 its outer flange bends the outer portion of the flange 1 down around the outer face of the die 12, as shown in Fig. 4. In its descent the die 16 pressed the ring die 18 downwardly in the recess in the die plate 11 and compressed the spring support upon which said ring die 40 is mounted. consequently when the dies are again raised the ring die 18 will be forced upwardly so as to loosen the hoop from the die 12 and permit it to be carried away from the press preparatory to the introduction of a fresh blank.

50 In order to insure the lifting of the pressed hoop clear of the die 12 I magnetize the dies 16 and 17, or either of them, and in order that this magnetic attraction may be intermittent the magnetized die constitutes the pole piece of an electromagnet through the winding of which the electric circuit may be established when the die is at the lower portion of its movement and can be cut off as the die rises so as to demagnetize the same and permit the hoop to drop therefrom or be readily removed. In Fig. 7 I have illustrated one construction whereby this result 55 may be attained. In the construction there shown the plunger 14 is provided with a winding 45 of insulated wire, whose opposite ends communicate with terminal plates 46 and the underside of the cross head is 60 provided with plates 47 and 48 connected,

respectively, to the terminals of an electric circuit.

The plates 47 and 48 have spring fingers 49 which, when the plunger 14 reaches a certain point in its descent, contact with the plates 46 and establish an electric circuit through the winding 45 so as to convert the plungers 14 and 15 into the cores of an electromagnet of which the dies 16 and 17 are the pole pieces. The plates 46 are of such length that the magnetization of the dies 16 and 17 continues until they have completed their descent and have been raised far enough above the die 12 as to permit of the removal of the pressed ring, whereupon the spring fingers 49 cease to bear upon the plates 46, the circuit through the winding 45 is cut off, and the dies are therefore demagnetized so that the hoop will drop therefrom. The plungers 14 and 15 may have 85 independent wirings and electrical connections operating in the manner above described so that the dies 16 and 17 can be magnetized independent of one another, or but one of these dies may be magnetized, if 90 desired.

95 In order to prevent the magnetization of the fixed frame of the machine and the fixed die the cross head may be provided with an insulating bushing 50 for the passage of the plunger 14.

When the die 17 clamped the flange 2 of the blank against the upper face of the ring die 18 it also served to flatten out any wrinkles or corrugations which may have 100 been formed in said flange while the same was being bent edgewise into ring form. As the die 16 bends the projecting portion of the flange 1 of the blank down around the outer face of the die 12 wrinkles will also be 105 formed at and near the free edge of said flange because of the contraction in diameter to which it is subjected, but as the die 16 continues its descent these wrinkles will also be flattened by the time the die 16 reaches 110 the limit of its downward movement, or if it is not desired to so flatten them the downward movement of the die 16 may be arrested at a higher point.

115 The dies 16 and 17 may be screwed or otherwise detachably mounted upon the lower ends of the plungers 14 and 15, respectively, so as to be readily removed and replaced, and the die plate 11 with its annular die 12 and ring die 18 can also be readily 120 removed from the bed plate 10 of the press so as to permit of the quick substitution of one set of dies for another to accord with differences in the diameter or cross sectional form of the hoop to be produced. By raising or lowering the boxes 26 of the shaft 23 by means of the gibs 28 the limit of descent of the dies 16 and 17 can be regulated and the press thus adapted for acting upon sheet metal of different degrees of thickness. 130

I claim:

1. The combination, in a die press, of an annular die, a pair of die-carrying plungers, and means for independently operating said plungers, the die of one plunger pressing the blank against the face of the annular die and forwardly along one side of the same, and the die of the other plunger pressing the blank forwardly against the other side of said annular die.
2. The combination, in a die press, of an annular forming die, a die inside of the same, a pair of die carrying plungers, and means for independently operating said plungers, the die of one plunger pressing the outer portion of the blank forwardly against the outer side of the annular die, and the die of the other plunger pressing the blank against the face of the annular die, forwardly against the inner side of said annular die and against the face of the inner die.
3. The combination, in a die press, of an annular forming die, a yieldingly mounted die inside of the same, and a die-carrying plunger whose die presses the blank against the face of the annular die, forwardly against the inner side of said annular die and against the face of said yieldingly mounted inner die.
4. The combination, in a die press, of an annular forming die, a die inside of the same, a pair of die-carrying plungers, and means for independently operating said plungers, the die of one plunger pressing the blank against the face of the annular die, forwardly against the inner side of the same and against the face of the inner die, and the die of the other plunger pressing the outer portion of the blank forwardly against the outer side of the annular die.
5. The combination, in a die press, of an annular forming die, a yieldingly mounted die inside of the same, a pair of die carrying plungers, and means for independently operating said plungers, the die of one plunger pressing the blank against the face of the annular die, forwardly against the inner side of the same and against the face of the yieldingly mounted inner die, and the die of the other plunger pressing the outer portion of the blank forwardly against the outer face of said annular die.
6. The combination, in a die press, of a pair of vertically movable die-carrying plungers, cam mechanism for projecting the same and for retracting one of the plungers, and a connection between said plungers whereby one is caused to retract the other.
7. The combination, in a die press, of a pair of movable die carrying plungers, cam mechanism for projecting the same and for retracting one of the plungers, and a lost

motion connection between said plungers whereby one is caused to retract the other 65 after the first plunger has completed a portion of its retracting movement.

8. The combination, in a die press, of an annular die, a pair of plungers, one disposed within the other and guided thereby in its 70 longitudinal movement, an inverted cup-shaped die carried by the outer plunger and constructed to press the outer portion of the blank forwardly around the outer side of said annular die, a die carried by the inner plunger and operating within said outer die, said inner die being constructed to press the inner portion of the blank forwardly around the inner side of said annular die and means for independently depressing 80 said plungers.

9. The combination, in a die press, of a die carrying plunger, a shaft having cam mechanism for projecting said plunger, a shaft which is also acted upon by the same 85 cam mechanism which projects the plunger, and links connecting said latter shaft and the plunger whereby the same cam mechanism which projects the plunger is also caused to retract the same. 90

10. The combination, in a die press, of a fixed die, a movable die, a plunger carrying the latter, a shaft having cam mechanism for projecting said plunger, and means for raising and lowering said shaft in respect 95 to the fixed die.

11. The combination, in a die press, of a die carrying plunger, a shaft having cam mechanism for projecting said plunger, boxes carrying said shaft, and adjustable 100 supporting gibs for said boxes whereby they can be raised or lowered.

12. The combination, in a die press, of a fixed die, and a movable die operating in conjunction therewith, said movable die being magnetized so as to lift the pressed object from the fixed die on the retraction of the movable die. 105

13. A die press in which are combined two independently operating dies, means for simultaneously magnetizing both of said dies, and means for simultaneously demagnetizing the same. 110

14. A die press in which are combined two independently operating dies, one inside of 115 the other, means for simultaneously magnetizing both of said dies, and means for simultaneously demagnetizing the same.

In testimony whereof, I have signed my name to this specification, in the presence 120 of two subscribing witnesses.

EDWARD W. ROBINSON.
